[57] CLAIM

The ornamental design for an oil burner preheater unit,
as shown.

DESCRIPTION

FIG. 1 is a perspective view of the oil burner preheater unit embodying the design of the present invention;
FIG. 2 is a front elevational view thereof;
FIG. 3 is a rear elevational view thereof;
FIG. 4 is a side elevational view thereof;
FIG. 5 is a side elevational view thereof;
FIG. 6 is a top plan view thereof; and,
FIG. 7 is a bottom plan view thereof.

FIG. 1

FIG. 6

FIG. 7

FIG. 3

FIG. 2

FIG. 5

FIG. 4
